BABY'S TEETHING RING

Myrtle J. Smith, P.O. Box 481, Casa Grande, Ariz.,
assignor of one-half to Leonard R. Nesary

Filed June 4, 1964, Ser. No. 80,276

Term of patent 14 years

(Cl. D83—8)

fig. 1

FIG. 1 is a plan view of the baby's teething ring showing my new design.

FIG. 2 is a side elevational view of the same.

FIG. 3 is a sectional view taken on the line 3—3 of FIG. 1.

I claim:

The ornamental design for a baby's teething ring, as shown.
